CLAIM

The ornamental design for slat for roller shutters, as shown and described.

DESCRIPTION

FIG. 1 is a front side view of a partial length of the slat for roller shutters;

FIG. 2 is a rear side view of a partial length of the slat for roller shutters;

FIG. 3 is an end view of the slat for roller shutters, wherein the opposite end is a mirror image thereof;

FIG. 4 is a top plan view of the partial length of the slat for roller shutters as shown in FIG. 1;

FIG. 5 is a bottom plan view of the partial length of the slat for roller shutters as shown in FIG. 1;

FIG. 6 is a front side perspective view of the slat for roller shutters; and,

FIG. 7 is a rear side perspective view of the slat for roller shutters.

The claimed design has been illustrated broken on one end to indicate indeterminate length.
